UNITED STATES PATENT OFFICE.

CARL LINDSTRÖM, OF BERLIN, GERMANY.

STAMP-AFFIXING MACHINE.

1,177,955.

Specification of Letters Patent. Patented Apr. 4, 1916.

Application filed May 13, 1913. Serial No. 767,369.

To all whom it may concern:

Be it known that I, CARL LINDSTRÖM, a subject of the King of Sweden and residing at Gr. Frankfurterstrasse, 137, Berlin, O., Germany, have invented certain new and useful Improvements in and Relating to Stamp-Affixing Machines, of which the following is a specification.

This invention relates to a machine for affixing stamps to letters or the like, in which, in contradistinction to existing machines, the letters to be stamped are fed into the machine for the purpose of stamping them, by cylinders which revolve in opposite directions, and which at the same time affix the stamp on the envelop by their rolling action. For this purpose two cylinders are provided according to this invention which move in opposite directions to each other. If now the letter to be stamped is placed between the two cylinders, it is gripped and advanced by the same, while at the same time one of the cylinders, during its rolling action, affixes a stamp which has previously been severed by the said cylinder from the stamp feeder, and moved past the moistener, so as to moisten it. For this purpose the cylinder, which affixes the stamp is in part constructed as a cam. This is necessary in order to insure that the said cylinder comes into contact with the moistener only at those places where it carries stamps on its surface. A prolonged contact would moisten also that part of the cylinder where there are no stamps, and thus endanger a reliable working of the machine.

Further in contradistinction to existing stamping machines it is possible to stamp envelops to any required postage value with the improved stamp affixing machine, without it being necessary to interrupt the working of the machine in order either to place different stamps in the same, or in order to throw the feeding device supplying the required different kind of stamps into operation. According to this invention a simple device is provided by means of which letters may be stamped with the same kind of stamps to any required value of postage, and which device allows the stamp severing means to come into operation only after the required number of stamps have been moved past the same.

In order to correctly indicate the number of stamps affixed by the machine, a suitable counting mechanism is provided for this

purpose according to this invention. This mechanism is connected to the adjusting mechanism and is so arranged that, depending upon the number of stamps to be affixed to a letter, it executes a greater or smaller movement, whereby a gear wheel also connected to the indicating device makes a greater or smaller revolution and thus turns the counting mechanism to the required extent, so that it indicates to correct number.

Further the stamp conveying device consists of a bundle of hooks which are provided with teeth, and which are more numerous than the stamp perforations. By this means it is insured that at least one hook engages with each perforation, and is thus compelled to advance the stamp.

One form of carrying the invention into effect is shown by way of example in the accompanying drawings, in which:

Figure 1 is a sectional front elevation of the improved stamp affixing machine, Fig. 2 is a section on the line A—A of Fig. 1, Fig. 3 is a section on the line B—B of Fig. 1 as seen from the right, Fig. 4 is a view of the counting and adjusting mechanisms, Fig. 5 shows the position of the eccentrics in relation to each other, which they assume when one stamp is affixed to each letter, and Fig. 6 is a similar view showing the relative position of the eccentrics when five stamps are affixed to each letter.

In carrying the invention into effect as shown in the drawings, the letter which is to be stamped is conveyed over the plate 2 of the casing 1 to the cylinders 3 and 4 which revolve in opposite directions. A slipping through of the letter between the cylinders without being stamped is prevented by the catch hooks 5, which are simultaneously raised into the position shown in dotted lines in Fig. 2 by a coil spring 69, when the cylinders 3 and 4 move clear of each other. To the cylinder 4 there is fixed the cam disk 6, which is provided with openings 7 arranged on that part of the cam disk which has the same diameter as the cylinder 4. Through these openings pins 8 protrude, which are held in their normal retracted position by the springs 9. In order to cause the pins to protrude from the openings 7, so as to hold fast the stamp there is provided in the interior of the cam disk 6, another cam disk 10, the cam surfaces 11 and 12 of which are so arranged that when the pins mount the cam surface

11, they are caused to project from their holes, and to engage with the stamp located above them, while when the said pins come into contact with the cam surface 12, they 5 recede into their holes under the action of their springs 9, as soon as the affixing of the stamp commences. The coil of stamps 13 is placed in the receptacle 14, and the stamps are supplied to the feeder hooks 17 10 by passing between the support 15 and the clamping spring 16. The aforesaid feeder which comprises a plurality of uniform hooks 17 placed side by side conveys the stamps under and past the plunger 18, to the 15 cylinder 6, and the roller 19. The plunger 18 is connected by the arm 70 to the eccentric III in such a manner that it remains raised, thus allowing the passage of the stamps until the projection 20 of the arm 20 70 slides down from the projection 21, and thus presses the plunger with its projection 71 against the stamp and thus arrests the same. Previously to this the roller 19 which pivots about 22 and which is connected to 25 the eccentric II by the arm 23, has been already caused to press against the stamp so as to enable the cylinder 6 to carry the stamp along with it. Further to the lever 23 and the eccentric II, there is connected 30 the moistening device, which is adapted to turn about the spindle 24, and which consists of an arm 25, at one end of which there is revolutely arranged a roller 27 covered with felt 26. Water from the tank 29 is 35 supplied to the roller 27 by the wick 28. The spring 30 continually presses the wick 28 against the roller 27. On the arm 25 there is arranged a roller 31, which bears against an arm 32, connected to the arm 23 40 and the eccentric II. The arm 32 is provided with a stop 33 which is arranged so that at the moment in which the roller 19 is again lifted (that is to say when the roller 34 has come up against the stop 35), the arm 45 46 25 raises the moistening roller 27. The roller 19 remains in contact with the cylinder 6 until the last stamp has passed the moistener. 36, 37, 38 and 39 are springs which hold the respective levers and arms 50 always in engagement with the eccentrics.

On the shaft 42 (Fig. 4), there is mounted the disk 53, which is provided with holes 54. Further the bell crank lever 55 is pivotally arranged on the said disk at 56. The other 55 end 57 of the aforesaid lever is adjustable, and by means of a pin it may be placed in any one of the holes 54. This lever end 57 is, however, fixed to a lever 58 also keyed on the shaft 42, and can be adjusted only 60 together with this lever. Close to the eccentric II, there is mounted on the shaft 42, another eccentric IV, which is also connected to the eccentric I and the lever 58, while to the disk 53 there are rigidly connected the eccentrics III and II.

By adjusting the bell crank lever 55 and thus also the lever 58, so as to vary the engagement with the holes 54, the eccentrics IV and I are each given a different position in relation to the eccentrics II and III. 70 The eccentrics II, and IV may be so adjusted in relation to each other that a gap is formed between the cams, as shown in Fig. 5, or that they form a direct continuation of each other, as shown in Fig. 6. In the one 75 case, where they leave a gap, the roller 34, of the arm 23 will traverse a shorter distance, so that the roller 19 will be in contact with the stamp and the cylinder 6 a shorter time, while similarly the moistening device 80 will lift the roller 27 earlier off the cylinder 6, than in the other case, in which the roller 34 must travel over the two cams which form a continuation of each other while the roller 19 and the moistener 27 85 come into operation, and consequently also the eccentric III is adjusted in relation to the eccentric IV so that depending upon the adjustment, the roller 19 will be held in the raised position a shorter or longer period so as to allow any desired number of stamps to pass unchecked underneath it. By inserting the pin 57 in one of the holes 54 all the eccentrics are rigidly interconnected. 90

Fig. 3 shows the driving mechanism for the cylinders. On the cylinder 4 there is keyed a gear wheel 40 which in its turn engages with a gear wheel 41, which is firmly keyed on the shaft 42. On this shaft 42 there are further mounted the eccentrics I, II and III, which operate the tearing off device, the moistening device, and the feeding device. To one end of the said shaft 42 there is attached a crank 43. On the shaft 42, there is further mounted the eccentric 44, which bears against the connecting rod 45 fixed to the shaft 46. On the shaft 46 there is further mounted the lever 47 to which is secured the cylinder 3, in which latter there are provided grooves 48 with 100 which the catch hooks 5 engage. 105

The mode of operation of the cylinder driving mechanism, is as follows:—When by turning the crank 43, the eccentric 44 depresses the connecting rod 45, then the lever 47 also depresses the cylinder 3. At the same time the projection 49 which is also fixed on the shaft 46 moves downward, and releases a pin 50, which is connected to the clamping spring 69. This spring is mounted on the shaft 51, and, owing to the fact that the pin 50 has now room for play, it presses the hooks 5 upward into the position shown in dotted lines in Fig. 2. The springs 52 move the cylinder 3 always back 110 again into the proper position. 115

Fig. 4 shows the adjusting mechanism in combination with the counting mechanism. In order to enable the counting mechanism to indicate the use of more than one stamp 120 125 130

for one letter, there is connected with the counting mechanism X a small gear wheel 59, which gears with a larger gear wheel 60 mounted on the shaft 61. To the gear wheel 60 there is fixed a ratchet wheel 62, with which there engages a drag pawl 63 which is pivoted at 64 to the lever 65, which turns about 61. Further, the rod 66 is connected up at 64 and engages at y with the bell crank lever 55. When the mechanism is adjusted to deliver one stamp for each letter, then the point y is near the center of the shaft 42. Consequently also the distance through which the drag pawl 63 turns the wheel 62, is very short (Fig. 4). If, however, the mechanism is adjusted for the delivery of more than one stamp for each envelop, e. g. five, as shown in Fig. 6, then the point y at the center of the shaft moves 20 farther away so that consequently the drag pawl 63, moves the wheel 62 through a greater distance. For this reason, the counting mechanism is in the first case turned through a distance corresponding to one 25 unit, while in the second case, which is mentioned by way of example, it is turned through a distance corresponding to five units.

The mode of operation of the stamp affixing machine is as follows:—When the cylinders 3 and 4 are over each other, and when the catch hooks 5 prevent the pushing through of the letters, the letter to be stamped is introduced into the machine by 30 moving it over the plate 2 closely along the edge 67. In this position the plunger 18 and the roller 19 are in operation. The plunger 18 holds the strip of stamps 13, fed forward by the feeder hooks 17, while the 35 roller 19 turns the released stamp toward that part of the cylinder 6, which has the larger diameter. At the same time, however, the pins 8 strike the stop 11, whereby they are caused to protrude through their 40 openings and thus grip the stamp. By continuing the turning of the crank, the stamp is severed from the coil 18, as the latter is arrested by the plunger 18, and the severed stamp is carried away by the pins 8 and 45 the cylinder 6. The severed stamp now reaches the moistening roller 27 which descends so that it brushes over the stamp moved past it, and thus moistens the same. At the same time therewith the cam action 50 of the eccentric 44 on the connecting rod 45 has ceased, so that the said rod raises the cylinder 3 through the medium of the spring 52, and depresses the catch hooks 5. The stamp is held in its position on the 55 circumference of the cylinder 6 by the pins 8 and is thus carried around and affixed to the letter which is moved along by the frictional contact of the two cylinders 3 and 4.

At the moment at which the cylinder 3 is 60 raised the feeder hooks 17 more backward,

while the plunger 18, the roller 19, and the moistening device 25, 27 are raised. After the letter has been stamped and left the machine at 68, the feeder hooks 17 again advance the strip of stamps 13, and move the same beneath the plunger 18, and the roller 19, whereupon the cycle of operations recommences.

In cases where more than one stamp is to be affixed to a letter, the procedure is the same, with the only difference that the plunger 18, the roller 19, and the moistening device 25, 27 remain a longer period in the locked position in consequence of the adjustment of the eccentric II in relation to 80 the eccentric IV. Only after the last of the required stamps has moved past the plunger 18, does the latter descend and thus arrest the movement of the following stamps, from which the released stamps are 85 severed by the pins 8 of the cylinder 6.

What I claim, is:—

1. In a postal stamp affixing machine, the combination of a pair of cylinders adapted to revolve in opposite directions for passing the postal matter from the stamp-affixing point, one of said cylinders serving also for conveying a strip of stamps to the said stamp-affixing point, a plunger adapted to hold back the strip of stamps while the 90 stamps required for the postal matter, are severed therefrom, a roller for pressing the severed stamps against the cylinder which is conveying them to the affixing point, and eccentrics for adjusting said roller, whereby the required number of stamps may be pulled forth from underneath said plunger and then severed from the strip on the next descent of said plunger and means co-operating with said cylinders for affixing the 100 stamps.

2. In a postal stamp affixing machine, the combination of a pair of oppositely revolving cylinders and a device for moistening the stamps when severed from the strip 110 comprising a roller mounted to rock and alternately contact directly with a moistening wick and the stamp to be attached, with eccentrics for influencing said moistening device in such a manner that the latter 115 is in an operative position only during the moistening of the stamps and means co-operating with said cylinders for affixing the stamps.

3. In a postal stamp affixing machine, the combination of a pair of cylinders adapted to revolve in opposite directions for passing the postal matter from the stamp-affixing point, one of said cylinders serving also for conveying a strip of stamps to the said 125 stamp-affixing point, a plunger adapted to hold back the strip of stamps while the stamps required for the postal matter, are severed therefrom, a roller for pressing the 130 severed stamps against the cylinder which

conveys them to the affixing point, and eccentric for adjusting said roller, whereby the required number of stamps may be pulled forth from underneath said plunger and then severed from the strip on the next descent of said plunger, counting mechanism for counting the number of stamps used and means for actuating same from said eccentric which effect the adjustment 10 of said plunger and said roller and means coöperating with said cylinders for affixing the stamps.

4. In a postal stamp affixing machine, means including a cylinder for passing the 15 postal matter from the stamp affixing point and for conveying a strip of stamps to said stamp affixing point, and a plurality of feeder hooks for advancing the stamp strip

on to the stamp conveying cylinder, said feeder hooks being arranged closely side by side whereby even when the perforations in the stamps vary, a reliable engagement of individual feeder hooks or separate bundles thereof with the individual stamp perforations is insured, stamp-retaining means 25 comprising a cylinder, an oscillable bearing for said cylinder, a lever for oscillating said bearing and a revoluble cam actuating said lever.

In testimony whereof I affix my signature 30 in presence of two witnesses.

CARL LINDSTRÖM.
